UNITED STATES PATENT OFFICE.

SIMEON W. WALES, OF NORTH ABINGTON, MASSACHUSETTS.

SPRING-WASHER.

SPECIFICATION forming part of Letters Patent No. 425,476, dated April 15, 1890.

Application filed January 16, 1890. Serial No. 337,122. (No model.)

To all whom it may concern:

Be it known that I, SIMEON W. WALES, of North Abington, county of Plymouth, State of Massachusetts, have invented an Improvement in Spring-Washers, of which the following description, in connection with the accompanying drawings, is a specification, like letters on the drawings representing like parts.

10 This invention has for its object to provide a metallic spring-washer of novel construction, which is adapted to be secured to the axle-box or hub of carriages, and, if desired, to the usual axle-nut, to take up lateral motion and prevent rattle.

15 My improved spring-washer may be made from a circular metallic blank or ring, preferably of sheet-steel, by cutting or splitting the said blank and folding a portion of the 20 said blank back upon itself to form a substantially semicircular washer, consisting of a base and a spring-arm integral with said base.

25 My invention therefore consists, essentially, of a metallic spring-washer, it consisting of a base and a spring-arm folded back upon the base and integral therewith, substantially as will be described.

30 Figure 1, in elevation, represents a metallic spring-washer embodying my invention. Fig. 2, in section and elevation, represents a sufficient portion of a carriage-axle and its 35 box or hub and nut provided with my improved spring-washer to enable my invention to be understood; and Fig. 3, an end view of the nut removed, showing the spring-washer in operative position.

35 The axle a , threaded at its end, as at a' , and provided at its opposite ends with the 40 usual shoulder a^2 , and the axle-box or hub a^3 may be of any usual or well-known construction.

45 In accordance with my invention the axle-box or hub a^3 is provided with a metallic spring-washer, which may be made substantially as shown in Fig. 1, it consisting of a flat substantially semicircular base b and a spring-arm b' , forming an integral part of the base b , the said spring-arm being formed by 50 folding or bending it back upon the base b' .

In practice the spring-washer may be placed within the axle-box or hub a^3 by springing its ends together, so that when the pressure is

released and the spring-washer is within the box it is automatically retained in position by the normal spring-action of the metal.

The metallic spring-washer is placed within the axle-box, so that the spring-arm b' bears against the shoulder a^2 , and as a result keeps the axle-box firmly pressed against its seat at its opposite end, which in the present instance is shown as a second spring-washer placed within the nut b^2 , screwed upon the threaded portion a' of the axle.

My improved metallic spring-washer is 65 very simple in construction, is cheap, and yet very effective in operation, as it takes up the end-play or lateral motion of the axle-box and prevents rattle.

Furthermore, the metallic spring-washer is 70 automatically retained in place within the axle-box or the nut b^2 when the said parts are removed from the axle, so that it is always in operative position when the axle-box or hub are placed upon the axle.

75 By forming the spring-arm so that it extends but part way back on the base b of the spring-washer any dirt or grit which may become lodged on the said arm will work off of it in the revolution of the axle-box, 80 and onto the base b , thus preventing the said dirt from becoming lodged between the base and the arm, and thereby preventing the spring action of the said arm from being destroyed.

85 It will be noticed that the spring-arm b' bears against the shoulders a^2 , and consequently the friction between the said surfaces is largely reduced, owing to the small amount of surface in contact.

90 I prefer to make the spring-washer of sheet metal; but I do not desire to limit myself in this respect, as the said washer might be made of steel wire.

95 I claim—

The herein-described metallic spring-washer, it consisting of a base b and a spring-arm b' , folded back upon the base and integral therewith, substantially as described.

100 In testimony whereof I have signed my name to this specification in the presence of two subscribing witnesses.

SIMEON W. WALES.
